UNITED STATES PATENT OFFICE.

HARRY BRIDGMAN SMITH, OF BROOKLYN, NEW YORK.

BOX AND METHOD OF MAKING THE SAME.

1,408,479.

Specification of Letters Patent. Patented Mar. 7, 1922.

Application filed December 31, 1920. Serial No. 434,313.

To all whom it may concern:

Be it known that I, HARRY BRIDGMAN SMITH, a citizen of the United States, and resident of Brooklyn, in the county of Kings 5 and State of New York, have invented certain new and useful Improvements in Boxes and Methods of Making the Same, of which the following is a specification.

My invention relates to a box of novel and 10 economical construction, and to a method of rapidly and economically making such boxes.

In several prior applications I have disclosed boxes and methods of making them, 15 in which a box blank assembly is first produced, either by bringing a shell blank and a cover blank together with adhesive between them and turning over marginal portions of the cover and securing them adhesively to margins of the shell blank, or by 20 bringing together continuous strips or webs of shell and cover material with adhesive properly supplied between them, turning over the margins of the cover strip and securing them to the shell strip, and severing the 25 combined strips to produce box blank assemblies, which are substantially identical with those produced by the "blank" or "separate" method. Such methods and boxes 30 have usually been devised so that all exposed parts of the completed boxes are covered by the cover paper, including all the outward edges of the shell.

The present box structure and method 35 resemble previous structures and methods referred to in a general way, but for certain classes of boxes it is found to be unnecessary to provide such a highly finished exterior and, more particularly it is found 40 that desirable boxes for many uses may be produced in which some of the outer shell edges are not covered by the cover paper. By omitting the covering of certain shell edges the method may be considerably 45 simplified and cheapened and the box may also be more economically produced regardless of the particular method employed.

In previous continuous assembly methods 50 of my invention, that is, methods in which continuous strips of shell and cover material are brought together as a preliminary to forming the complete box blank assemblies, it has usually been necessary to cut out portions of the continuous assembly 55 strip and also to sever portions of the strip

to produce complete blanks of desired forms. My present method avoids the necessity for cutting out portions of the strip assembly and reduces the operation of forming assembly blanks from the continuous assembly 60 strip practically to the operation of cutting off sections of suitable length. This simplification and economy in the continuous assembly method may be obtained without regard to whether the boxes to be made from 65 the blanks so produced are completely covered or not, that is, whether all exposed parts of the shell are protected by portions of the cover paper or some of them are exposed. 70

The characteristics and advantages of the invention are further sufficiently explained in connection with a detail description of the accompanying drawing, which shows structures and sufficiently illustrates certain 75 method steps embodying my invention; and after considering these exemplifications persons skilled in the art will understand that many variations may be made within the principles of the invention, and I contemplate the employment of any structures, 80 methods and method steps which are properly within the scope of the appended claims.

In the drawings:

Fig. 1 is a perspective view of a continuous blank assembly, illustrative also of certain steps in its production method. 85

Fig. 2 is a perspective view of a complete, severed, box blank assembly.

Fig. 3 is a reverse view of the same. 90

Fig. 4 shows the assembly with side wings folded up.

Fig. 5 shows the corner or end laps folded in.

Fig. 6 shows the end wings folded up 95 against the end laps.

Fig. 7 shows a complete box structure.

According to the continuous assembly method, sufficiently illustrated in Fig. 1, a continuous strip or web W of box shell material, usually card board of suitable thickness, is fed, most conveniently from a roll, not shown. A continuous strip or web X of cover material, usually relatively thinner paper of suitable quality and finish, is fed 100 into contact with the shell strip, usually also from a roll, and one of the strips is coated on one of the contacting faces with adhesive y. This may be applied to a surface of either strip, but most conveniently for cer- 110

tain reasons is preferably applied as here shown to the upper surface of the cover strip X, and this application of adhesive may be made by means of a roller 10 or 5 any other suitable instrumentality.

Previous to assembly contact of the strips the shell strip is usually perforated at regular intervals providing apertures w, usually rectangular, as shown. The cover strip 10 is usually substantially wider than the shell strip so that as the initial assembly is formed adhesively coated margins z of the cover strip extend beyond the edges of the overlying cover strip.

15 At a suitable point in the progress of the shell strip, or in the progress of the assembled strips, the shell strip, or both the shell and cover strip, as the case may be, are desirably creased or scored to facilitate 20 subsequent bending. In the present case the shell strip is scored along the longitudinal lines 12 previous to assembly contact and the assembled strips are scored along the transverse lines 13 after assembly contact; 25 or all of the scorings may be made after assembly contact, or all of the scorings may be made upon the shell strip only, before initial assembly.

As the respective strips advance in contact they are suitably pressed together and at a suitable point in their advance suitable instrumentalities are applied to turn over the cover margins z and press them in adhesive contact with margins of the shell strip, as shown in the left hand portion of 30 Fig. 1. At a convenient point in its advance the web assembly is then cut transversely as at 15, this transverse cut extending centrally through the shell apertures 40 w and through the portions of the cover paper underlying these apertures and thus a complete box blank assembly A, Fig. 2 is produced, comprising a body portion 20, side wings 21, end wings 22 and corner or 45 end laps 23, which are desirably disconnected from the adjacent end wings by slitting the blank assembly along the lines 24, this slitting operation being performed either before the blank A is severed from 50 the web assembly, or after, as may be convenient. The severing of the combined webs along the lines 15 also produces marginal portions z of the cover extending beyond the ends of the shell end wings 22, adhesively coated in the original application 55 of adhesive to the cover strip. In addition to designating parts of the blank assembly, the numerals 20 to 24, inclusive, more particularly designate parts of the severed shell blank and numerals 20' to 23' designate respectively similar parts of the severed cover blank.

60 The complete blank assembly as shown in Fig. 2 may otherwise be produced by the 65 separate method; that is, separate cover and

shell blanks of the same forms may be provided and brought into flatwise contact with adhesive between them and the margins z of the cover blank folded over and secured upon marginal portions of the shell blank. 70

The blank-assembly, produced in either way, is now shaped into complete box form, involving at a suitable point in the shaping process the application of adhesive to outer (lower) surfaces 25 of the assembly, these 75 surfaces being co-extensive with the outer surfaces of the assembly end laps 23. Regardless of the exact time in the complete method at which the adhesive is applied to the surfaces 25, the side wings 21 with their 80 connected end flaps 23 are folded up as shown in Fig. 4 and the end laps 25 are then folded in, as shown in Fig. 5, whereupon their inner edges may exactly or approximately meet, or these edges may be separated more or less, depending upon the dimensions of the blank, or the desired structural characteristics of the completed box. The end wings 22 are now folded up against the adhesive outer surfaces of the end laps 85 and pressed in engagement, as shown in Fig. 6, and the upstanding margins z of the cover end wings, with their inner surfaces coated by adhesive in the initial formation of the blank assembly, are now turned in and down 90 against inner surfaces of the end laps and pressed in position, producing a complete box structure shown in Fig. 7, in which all exposed surfaces and edges of the shell are completely enclosed and covered by the 100 cover paper, except edges e of the shell end wings 22.

As an alternative method of assembly, at a suitable time in the shaping of the blank a into box form, the shell end wings 22 may 105 be separated from the cover end wings 22', thus exposing inner surfaces of these wings both covered with adhesive, and the end or corner laps 25 may then be turned in and placed between these adhesive surfaces and 110 the formation of the box completed as above described in which case the edges e of the shell end wings will be overlapped and covered by the covered corner surfaces of the blank adjacent to the intersection of the 115 blank side wings and corner laps.

A suitable plunger or former is usually placed within the box structure as it is shaped into box form, and other instrumentalities are used; but a showing of these 120 devices is omitted for the sake of clearness; and all of the method steps may evidently be performed without the use of any instrumentalities, except hand instruments of the simplest sort.

125 I claim:—

1. A method of making boxes comprising bringing a strip of shell material provided with spaced apertures in contact with a strip of cover material, with adhesive between 130

them, and forming complete box blank assemblies by severing the combined strips on a single transverse line which intersects one of said shell apertures.

5 2. A method of making boxes comprising
bringing a strip of shell material provided
with spaced apertures in contact with a strip
of cover material with adhesive between
them and forming complete box blank as-
semblies by severing the combined strips on
10 a single transverse line which substantially
intersects the longitudinal center of one of
said shell apertures.

3. A method of making boxes comprising
15 advancing a continuous strip of shell ma-
terial having spaced apertures, applying ad-
hesive to a surface of a continuous strip of
cover material and bringing the adhesive
surface of the cover strip into contact with
20 a surface of the shell strip, folding projecting
marginal portions of the cover strip over
and securing them upon upper marginal
surfaces of the shell strip, and severing the
assembled strips on a transverse line inter-
25 secting one of the shell apertures to pro-
duce a box blank assembly.

4. A method of making boxes comprising advancing a continuous strip of shell material having apertures at regular intervals,
30 applying adhesive to a surface of a continuous strip of cover material and bringing the adhesive surface of the cover strip into contact with a surface of the shell strip, folding extending marginal portions of the
35 cover strip over and securing them upon upper marginal surfaces of the shell strip, and severing the assembled strips on a transverse line substantially intersecting the longitudinal center of one of the shell apertures to produce a box blank assembly.

5. A method of making boxes comprising advancing a continuous strip of shell material having apertures at regular intervals, applying adhesive to a surface of a continuous strip of cover material and bringing the adhesive surface of the cover strip into contact with a surface of the shell strip, folding extending marginal portions of the cover strip over and securing them upon opposite marginal surfaces of the shell strip, and severing the assembled strips on a transverse line substantially intersecting the longitudinal center of one of the shell apertures to produce a box blank assembly.

55 6. A method of making boxes comprising advancing a continuous strip of shell material having apertures at regular intervals, applying adhesive to a surface of a continuous strip of cover material and bringing the
60 adhesive surface of the cover strip into contact with a surface of the shell strip, folding extending marginal portions of the cover strip over and securing them upon opposite marginal surfaces of the shell strip, severing
65 the assembled strips on a transverse line sub-

stantially intersecting the longitudinal center of one of the shell apertures to produce a box blank assembly, and scoring the shell material along subsequent folding lines at a suitable stage in the production of the assembly blank.

7. A method of making boxes comprising advancing a continuous strip of shell material having apertures at regular intervals, applying adhesive to a surface of a continuous strip of cover material and bringing the adhesive surface of the cover strip into contact with a surface of the shell strip, folding extending marginal portions of the cover strip over and securing them upon opposite marginal surfaces of the shell strip, and severing the assembled strips on a transverse line substantially intersecting the longitudinal center of one of the shell apertures to produce a box blank assembly, and cutting the assembled materials on a plurality of lines to produce wing separations. 75 80 85

8. A method of making boxes comprising bringing a strip of shell material provided with spaced apertures in contact with a strip of cover material, with adhesive between them, and forming complete box blank assemblies by severing the combined strips on a single transverse line which intersects one of said shell apertures, and shaping the assembly into complete box form. 95

9. A method of making boxes comprising advancing a continuous strip of shell material having apertures at regular intervals, applying adhesive to a surface of a continuous strip of cover material and bringing the adhesive surface of the cover strip into contact with a surface of the shell strip, folding extending marginal portions of the cover strip over and securing them upon opposite marginal surfaces of the shell strip, severing the assembled strips on a transverse line substantially intersecting the longitudinal center of one of the shell apertures to produce a box blank assembly, and scoring the shell material along subsequent folding lines at a suitable stage in the production of the assembly-blank, and cutting the assembled materials on a plurality of lines to produce wing separations. 100 105 110 115

10. A method of making boxes comprising bringing a strip of shell material provided with spaced apertures in contact with a strip of cover material with adhesive between them and forming complete box blank assemblies by severing the combined strips on a single transverse line which substantially intersects the longitudinal center of one of said shell apertures, and shaping the assembly into complete box form. 120 125

11. In a method of producing boxes, the steps of advancing a continuous strip of shell material having regularly spaced rectangular apertures, advancing a continuous strip of wider cover material, bringing the 130

- strips into adhesive contact, folding over the margins of the cover material upon the shell strip, scoring or creasing one of the strips along subsequent folding lines and 5 producing individual box assembly blanks by severing the combined strips along a single transverse line substantially intersecting one of the shell openings.
12. In a method of producing boxes, the 10 steps of advancing a continuous strip of shell material having regularly spaced rectangular apertures, advancing a continuous strip of wider cover material, bringing the strips into adhesive contact, folding over the margins of the cover material and securing them adhesively upon the shell strip, scoring or 15 creasing one of the strips along subsequent folding lines, and producing individual box assembly blanks by severing the combined strips along a single transverse line substantially intersecting one of the shell openings.
13. In a method of producing boxes, the 20 steps of advancing a continuous strip of shell material having regularly spaced rectangular apertures, advancing a continuous strip of wider cover material, bringing the strips into adhesive contact, folding over the margins of the cover material upon the shell strip, scoring or creasing one of the strips 25 along subsequent folding lines, producing individual box assembly blanks by severing the combined strips along a single transverse line substantially intersecting one of the shell openings, and shaping the assembly 30 blank into box form.
14. In a method of producing boxes, the 35 steps of advancing a continuous strip of shell material having regularly spaced rectangular apertures, advancing a continuous strip of wider cover material, bringing the strips into adhesive contact, folding over the margins of the cover material and securing them adhesively upon the shell strip, scoring or 40 creasing one of the strips along subsequent folding lines, producing individual box assembly blanks by severing the combined strips along a single transverse line substantially intersecting one of the shell openings, and shaping the assembly blank into 45 box form.
15. A method of making boxes comprising producing a box-blank having a body, side and end wings, and end laps, and consisting of a sheet of shell material and a sheet of 50 cover material in adhesive contact, folding up the assembly side wings and turning in the end laps, bending up the assembly end wings and securing them against the outer surfaces of the end laps.
16. A method of making boxes comprising producing a box-blank having a body, side and end wings, and end laps, consisting of a 55 sheet of shell material and a sheet of cover material in adhesive contact, the cover end wings having margins extending beyond the 60 ends of the adjacent shell end wings, applying adhesive to outer surfaces of the assembly end laps, folding up the assembly side wings and turning in the end laps, bending up the assembly end wings and securing them against the adhesive surfaces of the end laps and turning in and adhesively 65 securing the extended margins of the cover end wings against inner surfaces of the assembly end laps.
17. A box structure having a body portion, sides and ends, the body portion and sides being entirely enclosed by cover material, and the ends comprising inturned end laps, shell end wings overlying the end laps 70 and cover end wings overlying outer surfaces of the shell end wings, certain side edges of the shell end wings being uncovered.
18. A box structure having a body portion, sides and ends, the body portion and 75 sides being entirely enclosed by cover material, and the ends comprising inturned end laps, shell end wings overlying and adhesively secured to the end laps, and cover end wings overlying outer surfaces of the shell 80 and wings, the side edges of the shell end wings being uncovered.
19. A box having a body portion, sides and ends, and consisting of a shell blank and a cover blank having approximately 85 corresponding body portions, side and end wings and end laps, portions of the cover blank entirely overlying exposed portions of the shell blank, except at the ends of the box, where edge portions of the shell end 90 wings are left more or less exposed by the arrangement of the cover end wings.
20. A box having a body portion, sides and ends, and consisting of a shell blank and a cover blank having approximately 95 corresponding body portions, side and end wings and end laps, marginal parts of the cover side wings being adhesively secured to inner margins of the shell side wings, portions of the cover blank entirely overlying 100 exposed portions of the shell blank, except at the ends of the box where edge portions of the shell end wings are left more or less exposed by the arrangement of the cover end wings.
21. A box having a body portion, sides and ends, and consisting of a shell blank and a cover blank having approximately 105 corresponding body portions, side and end wings and end laps, the ends of the box comprising the inturned shell end laps, shell end wings upturned and adhesively secured to the outer surfaces of the end laps, and cover end wings overlying the outer surfaces of the shell end wings and having marginal 110 portions inturned and adhesively secured to inner faces of the end laps.
22. A box having a body portion, sides and ends, and consisting of a shell blank and a cover blank having approximately 115 corresponding body portions, side and end wings and end laps, the ends of the box comprising the inturned shell end laps, shell end wings upturned and adhesively secured to the outer surfaces of the end laps, and cover end wings overlying the outer surfaces of the shell end wings and having marginal 120 portions inturned and adhesively secured to inner faces of the end laps.
- 65 wings having margins extending beyond the 125 ends of the adjacent shell end wings, applying adhesive to outer surfaces of the assembly end laps, folding up the assembly side wings and turning in the end laps, bending up the assembly end wings and securing them against the adhesive surfaces of the end laps and turning in and adhesively securing the extended margins of the cover end wings against inner surfaces of the assembly end laps.

- sponding body portions, side and end wings and end laps, the ends of the box comprising the inturned shell end laps with overlying cover end laps, shell end wings upturned and 5 adhesively secured to the outer surfaces of the end laps and cover end wings overlying the outer surfaces of the shell end wings and having marginal portions inturned and adhesively secured to inner faces of the end 10 laps.
23. A box having a body portion, sides and ends and consisting of a shell blank and a cover blank having approximately corresponding body portions, side and end wings 15 and end laps, the ends of the box comprising the inturned shell end laps with overlying cover end laps, shell end wings upturned and adhesively secured to the outer surfaces of the end laps, and cover end wings overlying 20 the outer surfaces of the shell end wings and adhesively secured thereto, the cover end wings leaving edges of the shell end wings more-or-less exposed.
24. A box having a body portion, sides and ends, and consisting of a shell blank and 25 a cover blank having approximately corresponding body portions, side and end wings and end laps, the ends of the box comprising the inturned shell end laps with overlying cover end laps, shell end wings upturned and 30 adhesively secured to the outer surfaces of the end laps, and cover end wings overlying the outer surfaces of the shell end wings and having marginal portions inturned and adhesively secured to inner faces of the end 35 laps, the cover end wings leaving edges of the shell end wings more or less exposed.

Signed at New York city, in the county of New York and State of New York, this 21st day of December, A. D. 1920.

HARRY BRIDGMAN SMITH.
